CLAIM

The ornamental design for an aspirator, as shown and described.

DESCRIPTION

FIG. 1 is a perspective view of an aspirator embodying the new design.

FIG. 2 is a plan view of the right side of the aspirator shown in FIG. 1.

FIG. 3 is a plan view of the left side of the aspirator shown in FIG. 1.

FIG. 4 is a front plan view of the aspirator shown in FIG. 1.

FIG. 5 is a rear plan view of the aspirator shown in FIG. 1.

FIG. 6 is a top plan view of the aspirator shown in FIG. 1; and,

FIG. 7 is a bottom plan view of the aspirator shown in FIG. 1.

The broken line showing in FIG. 7 is for illustrative purposes only and forms no part of the claimed design.
